UNITED STATES PATENT OFFICE

MILTON W. UECKER, OF ELKADER, IOWA

CHECK FILE

Application filed May 26, 1930. Serial No. 455,668.

The invention relates to an advertising novelty to be used in the bank trade and is a handy file for canceled checks comprising of the following parts—

- 5 1. A collapsible box or suitable container upon the front and sides of which are to appear advertising matter.
- 2. A set of index cards.
- 3. A folding self-adjusting support the
- 10 purpose of which is to hold the index cards in an upright position and at the same time allow easy access to filed matter at all times.
- 4. A plain card insert for record purposes.

One form of the invention is illustrated 15 in the accompanying drawing in which Fig. 1 shows a front view of the entire file; Fig. 2 shows an end view; Fig. 3 shows a view looking down at the top of the file; Fig. 4 shows the support before folding; Fig. 5 shows on 20 a reduced scale a blank for the collapsible container; Fig. 6 shows a single index card and Fig. 7 shows the plain card insert which may be used for a record card.

Referring to Fig. 2 of the drawing which 25 shows an end view of the assembled file: It will be noticed that the follower is placed behind the index cards and between these and the back part of the container and that the follower represents a large W. The front 30 part of the W presses firmly against the index cards holding them upright and compact and being hinged at the bottom and free at the top it bends back on slight pressure thus allowing easy access to the filed matter. As 35 the file is filled the three bends of the W follower are automatically pressed together until the four sides are compacted. Should any filed matter be removed from the file the follower expands thus taking up the space vacated. Other self-adjusting followers have 40 been invented but they did not all hold the index matter upright and compact at all times. The reason that they will not stand upright is because the point of contact is either 45 above or below the center of gravity thus allowing the filed matter to either kick in at the bottom or fall over at the top thus causing the filed matter to wedge and prevent 50 self-adjustment.

Some of the advantages of this invention are—

1st.—It can be knocked-down and folded so that it may be enclosed in an envelope for distribution.

2nd.—Its simple construction which enables it to be produced at a small cost.

3rd.—Its easy assemblage which makes it possible for any individual to assemble it quickly.

4th.—The self-adjusting support which holds the index cards and filed matter upright and compact, allows easy access to the filed matter and automatically adjusts itself as the file is filled.

I make no claim to the collapsible box shown nor do I wish to limit my invention to the specific box here shown but give this merely to give the idea of a collapsible container. Neither do I claim the idea of an index card; but

I claim;

1. The combination in an index file, for canceled checks, of a collapsible box; a set of index cards including a card insert for record purposes and a self-adjusting expanding support resembling an upright W placed behind index cards in container, holding index cards compact and upright, allowing easy access to filed matter and preventing index cards from wedging by kicking in at top or bottom.

2. A self-adjusting support consisting of a strip of flexible resilient sheet material folded in three places so as to take the shape of a large W forming a support for the index cards and filed matter adapted to automatically adjust itself as the checks are filed.

MILTON W. UECKER.
